UNITED STATES PATENT OFFICE.

GEORGE H. GARRISON, OF BRIDGEPORT, CONNECTICUT.

ACTION LOCK FOR FIREARMS.

Application filed June 1, 1920. Serial No. 335,705.

To all whom it may concern:

Be it known that I, GEORGE H. GARRISON, a citizen of the United States, residing at Bridgeport, in the county of Fairfield and State of Connecticut, have invented certain new and useful Improvements in Action Locks for Firearms, of which the following is a specification.

This invention relates to repeating firearms and particularly to improvements in action locks for such arms.

It is customary to provide means for locking the reloading mechanism of a repeating firearm at all times when the arm is in condition for firing, as it would otherwise often occur that unused ammunition would be wasted because unfired cartridges would occasionally be ejected from the arm. Furthermore, such an arm would be very dangerous as it might be possible to discharge the arm while partly open or it might be opened so soon after the firing of the charge as to be dangerous. For this reason it is customary to provide repeating firearms with means for locking the action until the arm is fired. This generally consists in a device for locking the means which actuates the repeating mechanism of the arm. In slide action arms mechanism is generally provided for locking the action slide. An example of this is found in the so-called #12 Remington rifle made according to Patents #908,883; 936,806; 953,797; 1,023,169 and others.

In this arm and many others the action is unlocked by the falling of the hammer. It has been found that if the operating handle of this arm is strongly drawn rearward at the time of firing the resistance to unlocking may become so great as to prevent the hammer reaching the firing pin or at least reducing its impact so greatly as to cause misfires or hang-fires. Sometimes, also, the cartridge is exploded but, on account of a rear draft on the handle, the action is opened too early, allowing the shell to blow back out of the chamber.

It is the object of this invention to overcome these objections and while the invention is disclosed as embodied in a particular type of firearm, it is to be understood that the underlying principle is applicable to many arms differing greatly in construction from that shown in the drawing.

In said drawing Fig. 1 is a side view, partly in section, of a firearm embodying

the present invention, the parts being shown in position for firing and the action bar being locked.

Fig. 2 is a similar view, the hammer, however, having sprung partly forward, the action remaining locked.

In Fig. 3 the hammer has reached its forward position and fired the cartridge, the action remaining locked.

In Fig. 4 the action is shown unlocked and the parts ready for reloading.

In said drawings the numeral 11 indicates the receiver, to the rear portion of which is attached a suitable stock 12 and to its forward end is secured the barrel 13 in any desired way. The receiver is made hollow to provide a mechanism chamber, wherein is located for longitudinal reciprocation a breech block 14 formed with a locking lug 75 15 normally bearing against a locking shoulder 16 in the receiver. The lower part of the breech block is formed with an operating lug 17 cooperating with an action slide 18, in any suitable way, preferably in the manner fully described in the patents referred to above. The action slide has a rearward bearing in an opening 19 in the forward end of the receiver and it extends forwardly under the barrel, and is provided, preferably, with an operating handle 20. In the particular arm shown, the action slide is formed hollow and performs also the function of a cartridge magazine. The bottom of the receiver is closed by a trigger plate 21 permanently attached to the stock, which serves as a support for the trigger 22, mounted on a pivot 27, and also carries the bearing sleeve 28 upon which are pivotally supported the hammer 29 and the latch lever 30 which in this arm also serves as a carrier and may be constructed as is fully shown and described in said patents. This latch lever is provided with a rearwardly extending arm 31 against which bears a plunger 32 seated on a coil spring 33 located in a recess in the trigger, whereby the trigger is spring tensioned forwardly and the locking latch is spring tensioned downwardly at its forward end. The hammer is spring impelled forwardly by the main spring 35 located in the stock and surrounding the main spring rod 36. This rod is connected to the hammer by means of the pivot pin 37, carried by the hammer and passing through the elongated slot 38 in the forward end of the main spring rod. This slot preferably

extends in the general direction shown, so as to be substantially in the line of movement of the pin 37 when the hammer is forward. This construction allows for considerable play between the main spring rod and the hammer which produces a desirable result which will be referred to later. The main spring rod is formed with a contact face 39 which is engageable at certain 10 times with the arm 31 of the locking latch serving to depress said arm and to lift the locking latch for unlocking the action slide.

The bottom part of the action bar 18 is slotted so as to receive the latch lever 30 when the action bar is retracted. Mounted immediately in front of the locking latch is a stop lug 40 carried by the action bar. This lug is, in the normal position of the parts, located opposite the stop face 41 on 20 the latch lever 30, and therefore serves to prevent the retraction of the action bar and so locks the arm against reloading except under certain conditions. In the arm to which the invention is here shown applied the latch lever also serves as a carrier and for this reason the lug 40 is utilized also as a means for actuating the lever 30 to perform its carrier functions. On the closing movement of the mechanism, it lifts the carrier by moving forward in the cam race 43. On this account it is necessary that the lug 40 be mounted for transverse movement, which may be accomplished by having it formed upon a spring arm 44 pinned to the 30 action bar at 45. Immediately below the stop face 41, the latch lever is beveled off as at 46 so that when the latch lever is raised for unlocking, as in Fig. 4, this bevel face will be located opposite the stop lug 40, whereby retraction of the action bar is permitted. It is to be understood, however, that the transverse movement of the lug 40 is made necessary only to operate the lever 30 as a carrier.

With the parts as shown in Fig. 1 the action is locked and it will be impossible to open the action without firing the gun unless the lever 30 is first raised manually. This may be accomplished by lifting the lever with the finger, the lever being accessible on account of the depression 42 in the trigger plate.

Operation: If the trigger is pulled with the parts in the position shown in Fig. 1, the spring 35 will force the hammer forwardly into the position shown in Fig. 2, at which time the contact face 39 engages the arm 31 and tends to unlock the action. If the operating handle is not strongly retracted, and therefore no great resistance to unlocking is present, the lever 30 will immediately be raised to the position shown in Fig. 4, during which time the hammer is moving further forward to fire the cartridge. If, however, the handle is strongly retracted,

the action is not unlocked, the lever 30 remaining in the position shown in Fig. 2 while the slot 38 permits the hammer to move forwardly on account of its momentum to the position shown in Fig. 3, causing the explosion of the cartridge. During this movement the rod 36 does not move appreciably and the pin 37 moves toward the forward part of the slot 38. The contact face 39 on the rod 36 bears on the arm 31 and tends to depress the arm on account of the pressure of the spring 35 and the angular disposition of the slot, whereby the latch lever is spring impelled toward inoperative position. If now the pressure on the action bar is relieved, the main spring rod will move slightly forward under the pressure of spring 35 and will cause the contact face 39 to depress the arm 31 and raise the lever 30 for unlocking the action, the parts having now assumed the position shown in Fig. 4. During this movement the slot moves relative to the pin 37 whereby the pin is again positioned in the rear of the slot.

By this arrangement it is impossible to stop or retard the hammer by a strong rearward pull on the action slide. Also, it is impossible to open the action at the instant of firing, it being necessary first to relieve the rearward pull on the handle to allow the lever 30 to spring up to unlock the action, which provides a time interval during which the explosion takes place.

What I claim as my invention and desire to secure by Letters Patent of the United States is:—

1. In a firearm of the type having a firing chamber, breech mechanism closing the firing chamber, and operating mechanism for said breech mechanism, the combination of a latch normally blocking said operating mechanism, a hammer, means connected with said hammer for moving the latter and withdrawing said latch from operative position, said means being so connected with the hammer so as to permit of a further movement of said hammer independently of said means.

2. In a firearm of the type having a firing chamber, breech mechanism closing the firing chamber, and operating mechanism for said breech mechanism, the combination of a latch normally blocking said operating mechanism, impact means, a main spring and means intermediate said spring and impact means for withdrawing said latch from operative position, said means being so connected with the impact means as to permit of a further movement of said impact means independently of the intermediate means.

3. In a firearm of the type having a firing chamber, breech mechanism closing the firing chamber, and operating mechanism for said breech mechanism, the combination of a latch normally engaging and blocking said operating mechanism, a hammer, a

hammer spring, means connecting said spring and hammer for moving the latter and withdrawing said latch from operative position, said means being so connected with the hammer so as to permit of a further movement of said hammer independently of said means.

4. In a firearm of the type having a firing chamber, breech mechanism closing the firing chamber, and operating mechanism for said breech mechanism, the combination of a latch normally blocking said operating mechanism, a hammer, a hammer spring, a main spring rod bearing against said spring and formed with an angular slot, a pin mounted in said hammer and passing through said slot, and means on said rod engageable with said latch when the hammer is forward.

5. In a firearm of the type having a firing chamber, a breech block reciprocably mounted for closing said chamber, and a reciprocable action rod for operating said breech block, the combination of a latch normally blocking said action rod, a hammer, a hammer spring, means connecting said spring and hammer for moving the latter and withdrawing the said latch from operative position, said means being so connected with the hammer as to permit of a further movement of said hammer independently of said rod.

6. In a firearm of the type having a firing chamber, breech mechanism closing the firing chamber, and operating mechanism for said breech mechanism, the combination of a carrier normally blocking said operating mechanism, a hammer, a hammer spring, a rod connecting said spring and hammer for withdrawing said carrier from blocking position, said rod being so connected with the hammer as to permit of a further movement of said hammer independently of said rod.

7. In a firearm of the type having a firing chamber, breech mechanism closing the firing chamber, and operating mechanism for said

breech mechanism, the combination of a carrier normally blocking said operating mechanism, impact means, a main spring and means intermediate said spring and impact means for withdrawing said carrier from blocking position, said means being so connected with the impact means as to permit of a further movement of said impact means independently of the intermediate means.

8. In a firearm of the type having a firing chamber, a breech block reciprocably mounted for closing said chamber, and a reciprocable action rod for operating said breech block, the combination of a carrier normally blocking said action rod, a hammer, a hammer spring, a rod connecting said spring and hammer for withdrawing said carrier from blocking position, said rod being so connected with the hammer as to permit of a further movement of said hammer independently of said rod.

9. In a firearm of the type having a firing chamber, a breech mechanism, an action bar for operating said breech mechanism, the combination of a latch normally blocking said action bar, a hammer, a hammer spring, means connecting said spring and hammer for withdrawing said latch from blocking position, said means being connected with the hammer by a lost motion connection so as to permit a further movement of said hammer independently of said means.

10. In a firearm of the type having a firing chamber, breech mechanism closing the firing chamber, and operating mechanism for said breech mechanism, the combination of a latch normally blocking said operating mechanism, impact means, and connections between said latch and impact means for moving said latch to inoperative position, said connections comprising means on said latch engageable by means having a pin and slot connection with said impact means.

GEORGE H. GARRISON.
